UNITED STATES PATENT OFFICE.

JAMES T. MALLOY, OF OAKLAND, RHODE ISLAND, ASSIGNOR, BY MESNE ASSIGNMENTS, TO DRAPER CORPORATION, OF HOPEDALE, MASSACHUSETTS, A CORPORATION OF MAINE.

WEFT-REPLENISHING LOOM.

Application filed February 23, 1927. Serial No. 170,144.

The present invention relates to an improvement in weft replenishing looms.

In weft replenishing looms of the feeler controlled type, the loom is provided with a 5 feeler on one side of the warp which feels of the yarn in the shuttle and operates to cause weft replenishment upon a predetermined exhaustion of the filling on the bobbin. The hopper or magazine is located on 10 the opposite end of the loom from the feeler, and when a new bobbin is inserted in the shuttle, the thread extending from the selvage to the exhausted bobbin is severed by the temple thread cutter located on that side 15 of the loom. At the same time the shuttle feeler thread cutter moves rearward with the shuttle feeler, and its knife and clamp are opened during the rearward movement. It then operates to clamp the thread extending 20 from it to the temple thread cutter, and to cut the thread extending from it to the discharged bobbin so that the bobbin in falling from the shuttle may draw its thread out of the eye of the shuttle. The shuttle 25 feeler thread cutter and clamp holds one end of this piece of thread extending from it to the temple thread cutter, and after the insertion of a new bobbin this shuttle feeler thread cutter and clamp retreats and continues to hold this piece of thread. It has 30 been observed that sometimes this piece of thread will continue to be held by the shuttle feeler thread cutter and clamp until the next replenishment, and when the shuttle 35 feeler thread cutter and clamp is opened on its rearward movement to feel for the shuttle and cut and clamp the thread then being exhausted from the shuttle, the piece of thread being carried backward by the shuttle 40 feeler is caught in the lay and is carried into the shed on the next shot of the shuttle.

The object of the present invention is to prevent this accidental drawing into the cloth of pieces of thread from the shuttle 45 feeler thread cutter and clamp, and to this end provision is made for opening the shuttle feeler thread cutter and clamp after it has retreated from its clamping and cutting operation. The invention consists in the 50 construction hereinafter described and particularly defined in the claims.

In the accompanying drawings illustrating the preferred form of the invention, Fig. 1 is a cross-section of the breast beam of a

loom showing the shuttle feeler thread cutter and clamp, the temple thread cutter and the connections between; and Fig. 2 is a rear elevation of a portion of the breast beam of a loom showing the shape and mode of support of the connection between the temple thread cutter and the shuttle feeler thread cutter and clamp.

The illustrated embodiment of the invention is described as follows: The loom is a weft replenishing loom of the feeler controlled type provided on its right-hand end with a hopper indicated in a general way by the reference character 10. The breast beam 11 occupies the position shown in Fig. 1 with respect to the hopper 10. The shuttle 70 feeler thread cutter and clamp is indicated in a general way by the reference character 12. The temple thread cutter 13 is shown in outline, the hidden parts being illustrated in dash and dot lines, and the remainder of the temple and associated parts are omitted for the purpose of clearness. On the rear side of the breast beam 11 is supported the connection 14 between the temple thread cutter 13 and the shuttle feeler thread cutter and clamp 12. This connection 14 consists of a piece of wire, shown in elevation in Fig. 2. The straight portion or body of the wire is pivotally mounted on the ears 15 secured on the rear side of the breast beam. 85 At one end the upright arm 16 of the connection extends from the adjacent ear upwardly, and has its end in position to engage the finger or tail 44 upon the front end of the striker 35. Upon the opposite end of 90 the connection 14 is provided an arm 17, which extends downwardly and rearwardly from the adjacent ear 15 and carries upon its end the pin 18 which extends into the path of motion of the tail 19 of the temple 95 thread cutter 13.

The shuttle feeler thread cutter and clamp is constructed and operates as illustrated and described in the Northrop Patent No. 1,515,515, dated November 11, 1924. In the 100 operation of such shuttle feeler thread cutter and clamp, the clamp remains closed after it has seized the thread and severed it while in its rearward position. The normal mode of operation, therefore, of the loom is not interfered with except to the extent indicated 105 presently; that is to say, upon the forward movement of the shuttle feeler thread cutter

and clamp, the clamp moves forward and retains its hold upon the thread extending from the clamp to the temple. Then the device above described, consisting of the connection between the shuttle feeler thread cutter and clamp and the temple thread cutter, operates gradually to open the clamp, sufficient time being permitted to allow the temple thread cutter surely to cut the thread before the clamp of the shuttle feeler thread cutter and clamp has released its held end.

A complete description of the operation of the device is as follows: In the operation of the loom when the feeler indicates critical exhaustion, it causes the change shaft to be operated to cause the hopper to insert a fresh bobbin in the shuttle. Upon the beat of the lay on which the change occurs, the shuttle feeler swings rearwardly to make its feeling movement as the lay moves forward. During the rearward movement of the shuttle feeler the shuttle feeler thread cutter and clamp is opened wide, and assuming the proper boxing of the shuttle, the shuttle feeler engages the outgoing thread near the shuttle and then as the lay completes its forward movement it causes the shuttle feeler thread cutter and clamp to sever the thread and to clamp the end thereof and hold it. The transfer being completed, the end of the weft held by the shuttle feeler thread clamp extending to the selvage moves forward and continues temporarily to hold such thread end. Presently the other end of this piece of thread is cut by the temple thread cutter. Then the piece of thread held by the shuttle feeler thread clamp is held only by the thread clamp, previous to which it was held by the clamp and the cloth. With each beat of the lay the temple thread cutter is operated by the engagement of the lay with the tail of the cutter, and the latter oscillates the connecting wire, causing the distant end thereof at each forward beat of the lay gently to strike the tail of the shuttle feeler thread cutter and clamp. As a result of several beats of the lay these little blows of the connecting wire gradually open the shuttle feeler thread clamp until finally it releases the piece of thread held thereby and the piece of thread is permitted to fall out of the way without possibility of its being caught by the shuttle or shuttle thread and carried into the shed. While it is preferred to actuate the shuttle feeler thread clamp by the means described to open it after it has caught the thread from the outgoing bobbin, and while it still

holds it in forward position from the temple thread cutter, it is apparent that other means may be employed gradually to open the shuttle feeler thread clamp in the manner described. The present construction is preferred because of the contiguous position of the temple thread cutter and the convenience of actuating the shuttle feeler thread clamp therefrom.

Having thus described the invention, what is claimed is:

1. A weft replenishing loom of the filling feeler type having, in combination, a shuttle feeler provided with a thread cutter and clamp, means for closing the cutter and clamp on the forward beat of the lay upon replenishment to cut and clamp the thread extending from the cutter and clamp to the selvage, and means for delivering a series of light blows to the shuttle feeler thread clamp to open it gradually after a few beats of the lay subsequent to replenishment. 70

2. A weft replenishing loom as defined in claim 1, provided with a temple thread cutter actuated by the lay, and a connecting device between the temple thread cutter and the shuttle feeler thread cutter and clamp acting to gradually open the shuttle feeler thread clamp a sufficiently long time after replenishment to permit the cutting of the thread from the exhausted bobbin by the temple thread cutter before the shuttle feeler 75 thread clamp releases the thread. 80

3. In a replenishing loom, the combination of a shuttle feeler provided with a thread parter and clamp, means for causing the parter and clamp to part and clamp the thread between the shuttle and cloth selvage, a temple cutter, and means actuated by the temple cutter to open the parter and clamp when the latter are in front position and after the temple cutter has parted the 85 thread at the cloth selvage. 90

4. In a replenishing loom, the combination of a shuttle feeler provided with a thread parter and clamp, means for causing the parter and clamp to part and clamp the thread between the shuttle and cloth selvage, a temple cutter, and means constituted as a rocking member and actuated by the temple cutter to open the parter and clamp when the latter are in front position and after the temple cutter has parted the thread at the cloth selvage. 100 105 110

In testimony whereof I have signed my name to this specification.

JAMES T. MALLOY.
